UNITED STATES PATENT OFFICE.

HERMAN IHLENBURG, OF PHILADELPHIA, PENNSYLVANIA, ASSIGNOR TO
THE MACKELLAR, SMITHS & JORDAN COMPANY, OF SAME PLACE.

DESIGN FOR A FONT OF PRINTING-TYPE.

SPECIFICATION forming part of Design No. 20,546, dated March 3, 1891.

Application filed February 6, 1891. Serial No. 380,506. Term of patent 7 years.

To all whom it may concern:

Be it known that I, HERMAN IHLENBURG, a citizen of the United States, and a resident of Philadelphia, Pennsylvania, have invented a 5 Design for a Font of Type, of which the following is a specification.

My design for a font of type is clearly illustrated in the accompanying typographical impression, the general character of which is 10 that of the light-face fancy letter.

The general feature of the design is the peculiar scroll found in each letter of the upper-case, as well as some of the letters of the lower-case and the lines above some of the letters of the lower-case. The upper line of the 15 letter A terminates on the left-hand side with a scroll, the left vertical line joining this scroll. The lower line of the upper loop of the letter B terminates in a scroll, as well as the upper portion of the letter C. The lower line of the letter D terminates in a scroll, and the center lines of the letters E, F, and H terminate in a scroll. The upper portion of the letter G terminates in a scroll, and the lower portions of 20 the letters J, L, and T terminate in a scroll. One of the center lines of the letter M termin-

nates in a scroll. The upper and lower ends of the right-hand loop of the letter P, as well as the loop of the letter R, terminate in a scroll. The letter S terminates in a scroll both at top and bottom. The left-hand line of the letter V and both outside lines of the letter W, and one line of the letter X terminate in a scroll at the upper end. The line of the letter X also terminates in a scroll at 35 its lower end. The upper and lower lines of the letter Z terminate in a scroll. The letters a, e, i, o, u, and y of the lower-case have lines above them, and the letters f, g, j, k, v, w, x, and y, as well as the numerals, have scrolls. 40

I claim—

The design for a font of type, substantially as herein described, and as shown in the accompanying typographical impression.

In testimony whereof I have signed my 45 name to this specification in the presence of two subscribing witnesses.

HERMAN IHLENBURG.
